GEORGE F. GODLEY AND HENRY B. WHITTAKER, OF PHILADELPHIA, PA.,
ASSIGNORS OF ONE-THIRD TO GEORGE W. WEART, OF SAME PLACE.

SPRING-MOTOR.

SPECIFICATION forming part of Letters Patent No. 278,427, dated May 29, 1883.

Application filed December 14, 1882. (No model.)

To all whom it may concern:

Be it known that we, GEORGE F. GODLEY and HENRY B. WHITTAKER, citizens of the United States, residing at Philadelphia, in the county of Philadelphia and State of Pennsylvania, have invented certain new and useful Improvements in Spring-Motors, of which the following is a specification, reference being had therein to the accompanying drawings, where-

in— Figure 1 is a transverse vertical section of a spring-motor embodying our improvements. Figs. 2 and 3 are sections through the barrel, spring, and arbor on lines 1 1 and 2 2, Fig. 1, respectively. Fig. 4 is a perspective of one of the arbors or section of central shaft. Fig. 5 is a plan of brake mechanism. Figs. 6 and 7 are detail plans, illustrating modified form of attachment for the springs, arbors, and barrels. Fig. 8 is a perspective illustrating the mode of inserting the springs within the barrels. Fig. 9 is a detail perspective of removable bar or pin for the barrels. Fig. 10 is a sectional elevation of a modification of sectional shaft. Fig. 11 is an elevation of the drum or casing for the motor. Fig. 12 is a plan of same. Fig. 13 is a detail plan, showing modified form of spring attachment for the arbors. Fig. 14 is a perspective of arbor, illustrating preferable form of spring attachment therefor, and Fig. 15 is a detail perspective.

Our invention relates to that class of spring-motors wherein a number of cages or barrels, springs, and arbors or shafts are so combined that the measure of power obtained from all the springs is equivalent to that derived from one spring only, while the continuance of the power acquired is proportionate to the number of springs used, and has for its object to diminish the friction between the parts of the motor; to improved and inexpensive means for attaching the springs to the arbors and barrels; to an improved mode of inserting the springs within the barrels; to inexpensive and durable springs for the motor, which are made without being reheated for tempering them; to so arranging the springs within the barrels and connecting them thereto and to the arbors that the strain resulting from their winding will keep the arbors forming the sectional shaft in alignment with each arbor; to

the complete lubrication of the sectional shaft, and to simple and inexpensive brake mechanism whereby a cheap, durable, and effective spring-motor is produced.

Our invention accordingly consists of the novel combination, construction, and arrangement of parts, as hereinafter more fully described and claimed.

Referring to the accompanying drawings, A represents the central shaft, composed of sections or arbors a , a' , and a^2 , the last of which is secured to the base B, having connection with frame or plate B' by means of bars or pillars b.

C C represent the cages or motor-barrels, which are alike in construction. They are fitted to the arbors, as shown, and turn independently of each other, as also do the arbors a and a' . The latter have reduced portions or ends d d' , respectively, which taper downwardly, or are in the form of an inverted cone having rounded ends d^2 . The arbors a' and a^2 are provided with sockets d^3 , which receive the ends d d' , as shown, the end d of arbor a fitting in socket d^3 of arbor a' , and the end d' of the latter fitting in socket d^3 of arbor a^2 .

The bearing between the arbors is at the extreme point of the rounded ends d^2 , thereby reducing the bearing-surfaces between said parts to minimum, so as to avoid friction. The ends d d' being inverted cones, or tapering from above downward, and the sockets d^3 being cylindrical or parallel, a play-space, d^4 , is provided in each socket, so that when the arbors are bent

out of line said ends move or play in the spaces d^4 without binding against the walls of the sockets d^3 ; hence the arbors are free to revolve without inducing friction. Said spaces d^4 also serve as cups for a lubricant, to assure the proper oiling of the bearings of the arbors, as hereinafter explained.

The arbors a a^2 are each formed with a longitudinal slot, d^5 , while the arbor a' has two such slots diametrically arranged, as shown in Figs. 2, 3, and 14. Into these slots the inner or one end of the springs is inserted, as hereinafter fully set forth; and as two springs are secured to arbor a' , it is provided with two slots d^5 , or one for each spring secured thereto.

The base B has a flange, b' , forming a cup or pan, B^2 , and the winding-gear E, secured to

arbor a and operated by pinion e and shaft e' , is provided with an oil-cup, e^2 , having an axial opening, e^3 , so that oil poured into cup e^2 will flow into opening e^3 , to arbor a , thence down the same, lubricating its bearings in the barrels, and finally flows into the socket d^3 of arbor a' . The oil overflows said socket and trickles down the arbor a' to socket d^3 of arbor a^2 , and so on until it drips into pan B^2 , from which it may be drawn off by means of a stop-cock, (not shown in the drawings;) or it may be dipped out of said pan or otherwise removed therefrom.

The cages or motor-barrels C are each designed to contain two springs, F F , and have therefore two apartments, c c , with top, intermediate, and bottom plates, c^2 , c^3 , and c^4 , respectively, with bearings or openings c^5 for the central shaft or arbors. Said openings are formed with rounded or feather edges c^6 , so as to present as small a bearing-surface to the arbors as possible, and thereby diminish the friction. The plates c^2 , c^3 , and c^4 are connected together by posts g , g' , and g^2 . The posts g are in the form of pins or rods provided with shoulders g^3 , loosely fitting in openings g^4 in said plates, so as to be removable therefrom, and when they are withdrawn from the barrels extended lateral openings G are formed therein, as shown in Fig. 8, for purposes to be more fully explained. The posts g' are provided with vertical recesses or slots g^5 , for the reception of the outside ends of the springs, and with openings g^6 , for the passage of pins or bars f^2 . Said described parts of the barrels, save the pins g , are all cast or formed in one piece, or are integral with each other; hence the barrels are easily and cheaply made, and all expensive fitting of parts is avoided.

The springs F are formed of crucible cast-steel, so that when the ribbons for the springs are rolled and coiled into springs the latter do not have to be reheated to temper them, they being tempered in the act of rolling the ribbons; hence we dispense with all reheating processes and other expensive manipulations for giving the springs an even temper throughout their entire length. The use of such crucible-steel springs is an important part of our invention, as we are thereby able to obtain springs of great length which have corresponding or equal elasticity from end to end. They therefore can be made at a greatly-reduced cost, and are far more durable than the springs heretofore used. While we deem such springs preferable for our invention, we do not limit ourselves thereto, as the ordinary or other suitable springs may be used. As the springs are coiled their ends are bent or doubled up to form lugs or loops, as shown at f f' , and when designed to be inserted in the barrels the pins g are first withdrawn, and the coiled springs are then passed through openings G , as indicated in Fig. 8. Their outer ends, f' , are then slipped into the recesses g^5 in posts g' , and the pins f^2 passed through openings g^6 and inserted into the loops or openings of the ends

f' , to secure them to the barrels. The lower extremities of the pins f^2 rest upon the bottom of the recesses g^5 , as plainly shown in Fig. 1. The respective arbor or arbors are then passed through the bearings c^6 , as represented by dotted lines in said figure, and as they enter the barrels the inner ends, f , of the springs pass into the slots d^6 , and are thereby secured or attached to said arbors, whereupon the pins g are inserted in their places.

The posts g' of the barrels being located on opposite sides thereof, the two springs in each barrel have reverse or opposite connections therewith, as plainly shown in Figs. 2 and 3. Consequently when they unwind each such spring exerts a strain upon opposite sides of the arbors or sectional shaft, and as such strain or torsional action of one spring is opposed to that of the other, they neutralize each other, and the parts of the sectional shaft are thereby maintained in due alignment with one another, and friction is avoided, while heretofore such strain has fallen on one side of said shaft, bending it out of line, producing undue friction and causing a waste of spring-power.

H represents a drum or casing for the motor, composed of sections h h . Each section consists of two semi-cylindrical parts, h' h' , preferably of sheet metal, like steel or spring-brass or suitable material, hinged at h^2 , and having a locking pin or catch, h^3 . The casing being in sections, one or both sections may be removed, as desired, to obtain access to the motor. Upon the arbor a is a brake-wheel, I , and i i represent the brake-shoes, pivoted at i' to standard K .

L is a bar having a double wedge-shaped end, l , fitting in the openings i^2 i^3 in or between the brake-shoes, which are provided with a spring, M , for clutching or braking them on the wheel I . When the rod or bar L is drawn to the right, its wedges l draw or move the shoes i i apart and release them from the wheel I . The bar L may be operated by a treadle or hand-lever, as desired. So, too, a train of gearing may be attached to or mounted on the shafts a and k to obtain the desired speed. The springs are wound up by turning the shaft e' , a suitable ratchet being used in connection with the device, as in other spring-motors.

A motor so constructed can be made at a comparatively low cost. The friction being greatly diminished, the full effective power of the springs is obtained for the performance of the work, and but a small portion of it is lost, while in spring-motors as heretofore constructed a greater portion of the spring-power is wasted in overcoming the friction.

It will be noticed that the springs are connected to the barrels and arbors without riveting, screwing, or other permanent fastening. Consequently when broken they can be readily removed from the motor and replaced by new ones.

Instead of the slots in the arbors and barrels, lugs m may be formed thereon, and the ends of the spring be formed with loops m' , to em-

brace said lugs, as shown in Figs. 6 and 7. So, too, said slots in the arbor, &c., instead of being round or semicircular, may be parallel or tapering, as shown in Fig. 13, to receive the bent square ends of the spring.

We have shown two barrels containing two springs; but we do not wish to be understood as confining our invention thereto, as more than two barrels may be used; or a single barrel with one spring or other modifications may be substituted. So, too, while we have shown a central sectional shaft with slots or lugs for securing the springs thereto, we do not limit our improvements to the sectional shaft, as it may be one shaft throughout, or a rod surrounded by sleeves, to which the springs may be secured. Again, the tapering ends d^2 of the arbors may be dispensed with and a ball-and-socket bearing, O, substituted therefor, as shown in Fig. 10. If desired, the slots d^5 in the arbors may be formed as shown in Fig. 14.

What we claim is—

1. In a spring-motor, the combination, with a shaft or arbor and a barrel, each having a recess or slot which is parallel with the axial line of the arbor, of an intervening spring or springs, the ends of which are lugged or bent to enter and frictionally engage with said slots or recesses, substantially as shown and described.

2. The combination, in a spring-motor, of a spring having looped or bent ends, an arbor, and a barrel provided with recesses arranged parallel with the axial line of said arbor, for the reception of the ends of said springs, substantially as shown and described.

3. In a spring-motor, the combination of a sectional arbor, provided with a slot or recess, and a spring having loops at each end, one of which is inserted into the arbor-slot, and the other is placed within a corresponding slot in a barrel surrounding said spring and arbor, substantially as shown and described.

4. The combination, in a spring-motor, of a series of barrels having recesses or slots, a shaft or arbor provided with axial slots or recesses in its periphery, and a series of springs having a loop or bend at each end for insertion in the arbor and barrel slots, said springs having reverse end connections with said arbor and barrels, substantially as shown and described.

5. A sectional shaft for a spring-motor, composed of arbors a a' a^2 , &c., having tapering ends d^2 , slots d^5 , and sockets d^3 , substantially as shown and described.

6. In combination with a spring-motor, a sectional shaft composed of two or more arbors having a parallel socket at one end and an opposite conical or tapered end, the taper of the latter extending the full length of the adjacent socket, into which it enters, so that said tapered end can rock in said socket, as set forth.

7. The combination of shaft A, barrels C C, springs F F, bottom or pan B², oil-cup e², lo-

cated above the top of the first barrel, and having an opening, e³, leading to shaft A, whereby the oil in said cup finds its way through said opening and trickles down said shaft to lubricate all its bearings, substantially as set forth.

8. In combination with a spring-motor, the brake-wheel I, shoes i i, pivoted at i', having openings i² i³, and spring M, and the bar L, having double wedge end l, substantially as shown and described.

9. The combination, in a spring-motor, of a shaft and one or more barrels with springs which have reverse end connections with said barrels and arbors, substantially as shown and described.

10. The combination of shaft A and cages or barrels C C, having rounded or feather edge bearings e⁵, substantially as shown and described.

11. In a spring-motor, a cage or barrel, C, composed of two compartments having top, intermediate, and bottom plates and connecting posts, which are all cast in one piece or formed integral with each other, substantially as shown and described.

12. In a spring-motor, a cage or barrel having a top and a bottom plate with a removable pin, g, which passes through an opening in the top plate and rests upon the bottom plate, substantially as shown and described.

13. In a spring-motor, a cage or barrel, C, having posts g', with recesses g⁵, openings g⁶, and pins f², to connect with one of the ends of the springs, substantially as shown and described.

14. In a spring-motor, a cage or barrel, C, having plates e² e³ e⁴, with rounded edge openings e⁵, and posts g, g', and g², substantially as shown and described.

15. In a spring-motor, the mode of inserting the springs within the barrels or cages and securing their ends thereto and to the arbors, which consists of first coiling the springs with lugged ends, then forming lateral openings in the barrels, then passing the springs therethrough, then securing one end of the springs to the barrel, then inserting the arbor or shaft through the bearings in the barrels, so as to connect the arbor with the other end of the springs, and then closing said lateral openings, substantially as shown and described.

16. The herein-described spring for spring-motors, made of crucible cast-steel and tempered in the act of rolling and coiling it, substantially as specified.

17. A spring for a motor having lugs or loops formed on each end while being coiled, substantially as shown and described.

18. The spring F, having loops f f' at each end thereof, substantially as and for the purpose set forth.

19. The combination, in a spring-motor, of a vertical shaft, made in sections arranged to turn independently of each other, with a barrel containing two springs, said shaft and bar-

rel having recesses or lugs for engagement with the ends of the springs, substantially as shown and described.

20. In a spring-motor, the combination of 5 the following elements, viz: a shaft, one or more springs, one or more barrels, said springs having reverse connections with the shaft and barrels, an oil-cup for said shaft, brake mechanism, and an inclosing case or drum, substantially as shown and described.

21. In combination with a spring-motor, a drum or casing composed of two or more cy-

lindrical portions or sections, each of which consists of semi-cylindrical pieces h/h' , hinged and fastened together substantially as shown 15 and described.

In testimony whereof we affix our signatures in presence of two witnesses.

GEORGE F. GODLEY.
HENRY B. WHITTAKER.
